CLAIM

The ornamental design for a counterbalance lift truck, as shown and described.

DESCRIPTION

FIG. 1 is a perspective view of a counterbalance lift truck illustrating our new design;

FIG. 2 is a top, left and rear view of the design of FIG. 1; FIG. 3 is an enlarged right side view of the design of FIG. 1;

FIG. 4 is an enlarged left side view of the design of FIG. 1; FIG. 5 is an enlarged front view of the design of FIG. 1; FIG. 6 is an enlarged rear view of the design of FIG. 1; and, FIG. 7 is an enlarged top view of the design of FIG. 1. A portion of the mast is shown broken away in FIGS. 1-6 to indicate indeterminate length.
